ADJUSTABLE T-SQUARE

Filed Sept. 2, 1924

Attorneys.

UNITED STATES PATENT OFFICE.

ZSIVKO G. LAZAREVICH, OF SAN FRANCISCO, CALIFORNIA.

ADJUSTABLE T SQUARE.

Application filed September 2, 1924. Serial No. 735,439.

The present invention relates to improvements in T-squares, and its particular object is to provide an adjustable T-square which, while substantial and rugged in construction, is extremely simple and can be manufactured at low cost. It is particularly contemplated to pivotally connect the conventional blade to the head of a T-square by means of a disc secured to one of the members and a ring element secured to the other member allowing the disc to revolve therein. It is further proposed to utilize the simple arrangement for providing a graduation scale on either the ring or the disc and a pointer on the other member allowing the angular relation of the blade relative to the head to be easily determined. It is further proposed to form the disc and the ring for interlocking relation so as to hold the members against axial motion and to furthermore form the two members in such a manner that the engagement does not interfere with the turning of the blade, at least, through an angle of 180 degrees. Further objects and advantages of my device will appear as the specification proceeds.

The preferred form of my invention is illustrated in the accompanying drawing in which Figure 1 shows the head end of the T-square in plan, Figure 2 the same device in section taken along line II-II of Figure 1, Figure 3 an end view of the ring element used in the device shown in Figure 1, Figure 4 a plan view of the head end of a modified form of my T-square and Figure 6 a section through the same taken along the line VI-VI of Figure 5.

While I have shown only the preferred forms of the invention, it should be understood that various changes or modifications may be made within the scope of the claim hereto attached without departing from the spirit of the invention.

Referring first to the form shown in Figures 1 to 4, it appears that the head piece 1 is of conventional form and presents a straight edge 2 adapted to be placed against the edge of a drawing board, not shown in the drawing. A blade 3 of conventional form, a portion only of which is shown in the drawing, is rounded at its end, as shown at 4, and has a disc 5, preferably made of metal, secured thereto in concentric relation with its rounded end, the disc being either

glued to the blade or fastened thereto by means of small screws 6. A small, preferably circular, plate 7 is secured to the underside of the head piece 1 by means of screws 8, the head piece preferably being recessed, as shown in Fig. 2, to accommodate the plate and to allow the lower face thereof to be flush with the lower face of the head piece. The pin 9 extends upwardly from the plate 7 through the head piece and the blade 3 and the disc 5 are perforated in the center of the disc for pivotal engagement with the pin, a wing nut 10 threaded engaging the top end of the pin 9 for tightening the disc of the blade upon the head piece.

While this arrangement in itself would hold the blade to the head piece, I provide as a further means for preventing shifting of the blade relative to the head piece, the ring element 11 formed for revolving engagement with the disc 5 adapted to be secured to the head piece by means of screws 12. The ring element is recessed in its undersurface, as shown at 13 along a straight line 14, so as to allow of turning motion of the blade 3 through an angle of 180 degrees. While it is not necessary that the ring element be made a complete ring, I preferably allow the arms thereof to extend slightly beyond a semi-circle, as shown at 15, so that the disc is held against end-wise motion by the ring, irrespective of the holding engagement of the pin 9. The edge 4 of the blade extends beyond the dimensions of the disc and is in interlocking engagement with the underside of the ring so as to prevent axial motion of the blade 3 even after the wing nut 10 has been removed.

Either the disc or the ring element is provided with a graduated scale, as shown at 16 and a pointer graduation 17 on the other element allows an angular relation of the blade relative to the head piece to be read from the scale.

To assemble the T-square, it is only necessary to engage the blade and disc with the pin 9 and to screw the wing nut 10 down upon the pin and to thereafter secure the ring element 11 in place, whereupon the blade may be freely swung about its pivot within a range of 180 degrees and fastened in any position desired by a further tightening of the wing nut 10. In the form shown in Figures 5 and 6, the disc 18 is

secured to the head piece by means of screws 19 while the ring element 21 forms an integral part of the blade 22. As appears from the cross section shown in Figure 6, the ring element and the disc are interlocked by means of a tongue and groove arrangement 23 so that when the disc is fastened to the head piece by means of the screw 19, the blade is firmly held against endwise as well as axial motion, but remains free to revolve upon the disc. A graduation scale 24 is provided upon either ring or disc and a pointer 25 on the other element in adjacent relation to the scale.

15 I claim:

An adjustable T-square comprising a head member, a blade member pivotally and de-

tachably mounted on the head member, a circular disk member secured on the upper surface of the blade member adjacent the head member and adapted to turn with the blade member, said circular disk member being set in from that end of the blade member which is adjacent the head member, and an element secured to the head member, said element having a scale thereon and having an arcuate edge contacting with the arcuate edge of said circular disk member, the arcuate edge of said element being greater than a semi-circle, said element being cut away on its underside to allow the blade member to swing.
